AUTOMATIC TELEPHONE SWITCH

Filed June 16, 1922

Inventor:
Henry F. Dobbin

W.E. Beatty, A.T.Y.

UNITED STATES PATENT OFFICE.

HENRY F. DOBBIN, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC TELEPHONE SWITCH.

Application filed June 16, 1922. Serial No. 568,776.

To all whom it may concern:

Be it known that I, HENRY F. DOBBIN, a citizen of the United States, residing at New York, in the county of New York, State 5 of New York, have invented certain new and useful Improvements in Automatic Telephone Switches, of which the following is a full, clear, concise, and exact description.

This invention relates to automatic telephone exchange switching apparatus and more particularly to the so-called coordinate switches of the type adapted for establishing connections in an automatic telephone exchange system.

15 This invention is particularly adaptable to a switching system of the type disclosed in Patent No. 1,515,735 issued November 18, 1924 to Charles L. Goodrum and John N. Reynolds, but it will be apparent to those 20 skilled in the art that this invention may be applied equally well to perform other switching functions with few changes in the operating circuit.

The object of this invention is to provide 25 an economical and improved form of coordinate switch which will be simple, durable, and reliable in operation.

In accordance with the foregoing object the principal feature of this invention resides 30 in the provision of parallel banks or grids of passive conductors, together with a plurality of active conductors arranged on supports and extending in opposite directions into operable relation with their associated grid conductors.

Another feature is the provision of a selective mechanism in which each selective bar is common to a plurality of opposite rows of sets of active contacts.

40 Other features of invention and advantages will appear from the following detailed description and by the claims appended hereto, reference being had to the accompanying drawing in which: Fig. 1 is a 45 partial assembly view of said switch. Fig. 2 is a sectional view of Fig. 1, showing a set of active contacts in operated position, and Fig. 3 is a plan sectional view of Fig. 2.

The multiple bank conductors comprising 50 the wires, 1, 2, 3, 4 and 5, 6, 7, 8 of Fig. 1 are securely fastened at their ends to an insulating support 9 which is held securely on frame 30 by means of a strip 31 and a number of screws such as 32 and 33. Supports 10 and 11 are of insulating material

and are disposed at right angles to the direction of the lengths of the grid conductors and on them are mounted the flexible wire contact springs 12, 13, 14, 15 and 16, 17, 18, 19, etc. The supports 10 and 11 may be of 60 considerable length and may carry on opposite sides any desired number of sets of contact springs 12, 13, 14, 15 and 16, 17, 18, 19, etc., depending upon the switch capacity desired. For simplicity of illustration, however, only two such sets are shown on each side of support 11 in the side view of Fig. 2. The free ends of each set of contact springs 12, 13, 14, 15, and 16, 17, 18, 19 extend through apertures in a tie member or card 70 20, 20' each of which is held securely on the outer wires of its associated set by means of bushings 21, 21' each fitting tightly its respective wire. The cards 20, 20' are each provided with an arm 22, 22' adapted to 75 normally rest on the topmost conductor of its associated set of grid conductors, thus acting as a back stop for the active contact wires. The said active contacts are normally tensioned downwardly out of contact with 80 the grid conductors. With each double vertical row of sets of active contacts there is associated a vertical rotatable bar 23 which is provided at one end with an armature 24 arranged to be attracted by an electromagnet 85 25 whereby the bar 23 is rotated out of its normal position in response to each energization of said electromagnet. On each vertical bar 23 there is provided a number of resilient arms, 45, 45' each individual to a 90 set of contact springs. With each set of grid conductors 1, 2, 3, 4, etc., there is associated a horizontal rotatable bar 26, each of which is provided with an armature 27, and an electromagnet 28, whereby the bar is 95 rotated from normal to off-normal position. Each horizontal bar is provided with a number of arms 29. Each of these arms 29 is individually associated with a set of active contact wires, 12, 13, 14, 15, and an arm 45, 100 but it will be noted that normally arms 29 are free to move in a vertical path to one side of their respectively associated resilient arms 45. This is true, however, only when arm 45 associated with any arm 29 is in its 105 normal non-operated position as shown at 34, Fig. 1, wherein the arm 29 is shown in its off-normal ineffective position. When the vertical bar 23 is rotated out of its normal position by electromagnet 25 the end 110

portions 35 of arms 45 are moved into operable relation with their associated arms 29. Movement of bar 26 results in lifting the operating card 20 through the engagement of the resilient arm 45 by arm 29 so as to permit the active contact wires 12, 13, 14 and 15 to engage the link conductors 1, 2, 3 and 4 respectively. The operated grid bar together with arm 29 thereon remain in their off-normal position throughout the duration of the connection, but the vertical bars 23 may be immediately restored to normal, whereupon they may be immediately reoperated to cooperate with other horizontal bars 26 to establish other coexisting connections.

What is claimed is:

1. In a coordinate switch structure, stationary supports, sets of active conductors arranged on said stationary supports, and extending in opposite directions therefrom, sets of passive conductors arranged in engageable relation to said active conductors, and means for selectively operating said active contacts.
2. In a coordinate switch structure, insulative supports, sets of active conductors arranged on said supports and extending in different directions therefrom, sets of passive conductors associated therewith, a card individual to each set of said active contacts, means for selecting a plurality of sets of said active contacts which extend in different directions, and means for operating one of said selected sets.
3. In a coordinate switch structure, sets of passive contacts, sets of active contacts associated with each of said first-mentioned sets, a stationary support for said sets of active contacts, a duplex selective mechanism for said active contacts, and means for establishing connections between said active and passive contacts.
4. In a switching mechanism, a plurality of insulative supports, rows of sets of passive conductors, rows of sets of active conductors arranged on each of said insulative supports and extending in opposite directions therefrom, an operating card associated with each set of said active conductors, a duplex selective mechanism for said active contacts, and means for operating said card to effect connection between a set of said active and passive contacts.
5. In a switching mechanism, a plurality of stationary supports, rows of sets of pas-

sive contacts, rows of sets of active contacts arranged on each of said stationary supports and coordinate to the first-mentioned rows, an operating bar for each row of said passive contacts, a selecting bar common to two opposite rows of said active contacts, and means for operating said bars to effect interengagement between said active and passive contacts.

6. In a switching mechanism, a plurality of stationary supports, rows of sets of passive contacts, rows of sets of active contacts arranged diametrically opposite to each other on each of said stationary supports and extending laterally into engageable relation with said passive contacts, an operating card for each set of said active conductors, and means for selectively operating said active contacts.

7. In a switching mechanism, sets of normally disengaged active and passive contacts arranged in coordinate rows, an operating bar for each horizontal row of passive contacts, a selecting bar common to a plurality of rows of sets of said active contacts, and means to operate one set of said active contacts as a result of movement of said bars.

8. In a multiple coordinate switch, sets of normally disengaged active and passive contacts, arranged in coordinate rows, said active contacts being arranged in opposing rows, a duplex selective mechanism therefor, a tie member for each set of said active contacts, and means for operating said member to effect contact between said active and passive contacts at their crossing point.

9. A multiple coordinate switch comprising rows of sets of passive conductors, a stationary support, rows of active conductors on said support extending in opposite directions therefrom into engageable relation with said rows of passive conductors, and means to selectively operate said active contacts.

10. In a coordinate switch structure, insulative supports, sets of passive contacts, sets of active contacts arranged on said supports and extending in different directions therefrom, and common operating means for a plurality of said sets of contacts adapted to be reoperated to establish coexisting connections.

In witness whereof, I hereunto subscribe my name this 14th day of June, A. D. 1922.

HENRY F. DOBBIN.
